CROTCH CONSTRUCTION FOR GARMENTS

Victor A. Faegre, Bronx, N. Y.

Application August 28, 1943, Serial No. 500,406

6 Claims. (Cl. 2—43)

This invention relates to garment construction, and particularly to the crotch construction of women's body-supporting garments, such as "panty-girdles" and the like usually made of relatively heavy, yieldable or elastic body-compressing and body-conforming material which does not lend itself readily to crotch construction and which would be impractical from the standpoint of comfort and adaptability to use of the garment if extended in the crotch.

One object of the invention is to provide a garment of the type referred to in which a normally closed crotch construction is embodied, this construction being such as to make possible easy opening of the crotch when necessary.

Another object is to provide a construction the parts of which form, in effect, an overlapped fly crotch which, being normally in closed condition, affords the desired protection against exposure regardless of the posture of the wearer.

A further object is to embody in a crotch construction a feature of adjustable or automatic uplift in the wearer's pelvic region, at the same time serving to prevent the garment from riding up on the wearer's body.

Still another object is to provide the crotch-forming parts in such a manner that they may readily be removed and replaced when worn or soiled thus saving the more durable and costly body portion of the garment for further use.

A still further object is to provide a crotch having overlapping portions which, though normally closed over one another, may be separated and folded back out of the way, or tucked in down the leg embracing portions of the garment, thus positively removing them from the zone of possible soiling and leaving the hands of the wearer free.

Another object is to provide a crotch construction which lends itself readily to the inclusion of a removable, replaceable, protection cloth which will further prevent exposure and soiling during ordinary use, or which may take the form of a catamenial bandage when necessary.

In a preferred embodiment, though not limited thereto, the invention comprises a crotch for women's undergarments of the body embracing and conforming type, including two substantially similar pieces of suitable cloth having longitudinal edges in overlapping arrangement to provide a separable fly closure, this assembly being united to the garment at the crotch portion thereof along the edges of an appropriately formed crotch aperture, and the front portions of the cloth pieces where they overlap terminating in upwardly ex-

tending free extensions or tabs provided with fastening means having complements upon adjacent portions of the garment, the complementary fastening means when engaged serving to secure the free tabs to maintain the members of the crotch structure in overlapping, closed condition, and exerting a reactive tension between the crotch members and the body of the garment to provide an uplift at the crotch, and members arranged interiorly of the crotch structure, and secured to the inner overlapping portion adjacent to its front and rear extremities, to which a body-contacting protection cloth or the like may be removably attached, all as will be explained hereinafter more fully and finally claimed.

In the accompanying drawing illustrating the invention, in the several figures of which like parts are similarly designated,

Fig. 1 is a front view of a panty-girdle embodying the crotch construction as it appears upon a wearer.

Fig. 2 is a rear view of the garment shown in Fig. 1.

Fig. 3 is a fragmentary front view of the crotch portion of the garment with the fly of the crotch opened.

Fig. 4 is a view similar to Fig. 3 but illustrating a manner of holding the fly of the crotch in opened condition by tucking the free edges of the overlapping portions inside the leg portions and against the legs of the wearer.

Fig. 5 is an inside plan view of the crotch parts separate from the body of the garment, and

Fig. 6 is a fragmentary view similar to Fig. 1 but showing a modification of the form of the free tabs.

Referring particularly to Figs. 1 and 2, it will be seen that the body 1 of the garment, shown as a panty-girdle, is of conventional form, but in order to accommodate the fly crotch construction of the invention the leg portions and parts adjacent to the crotch at front and rear are cut away to provide an opening the edges of which are joined to the crotch-forming parts of the invention by front and rear seams 2 and 3, respectively.

As shown in Fig. 5, the crotch parts include similarly shaped and finished pieces of suitable cloth 4 and 5, preferably soft and pliable, arranged with their similar longitudinal edges 6 and 7, respectively, in substantial overlapping relation to provide a fly, the opposite edges 8 and 9 being hemmed and joined in the bottom hems 10 of the leg portions of the garment. The raw, or unfinished, edges 11, 11' and 12, 12' of the parts 4

and 5 are, as above stated, joined in the seams 2 and 3 at the crotch opening.

The edges 11, 11' of the parts 4 and 5 are provided, in line with the overlapping fly-forming portions, with free extensions or tabs 13 and 14, respectively, provided with fastening means 15, such as members of the hook-and-eye fasteners, the complements 16 of which are so located upon adjacent portions of the garment that when worn, with fly crotch closed, an uplift, in the form of a reactive tension between the body 1 and crotch structure will be produced to insure a comfortable close fit and prevent riding up of the garment upon the wearer's body. Also, the slight lateral offset of the fastener elements 16 has a tendency to hold the fly parts in overlapped condition and the crotch closed.

Obviously, fastening devices other than hooks and eyes may be used, such as the snap fasteners 17 shown in Fig. 6, and, instead of relying upon alteration of the position of the complementary fastener parts, the tabs may be in the form of adjustable straps, or they may be made as elastic straps or tabs 13', 14', Fig. 6, in order to provide, automatically, for the proper amount of uplift tension.

Referring to Figs. 3, 4 and 5, and particularly to Fig. 5, it will be seen that the overlapping inner fly portion of the part 5 may be, and preferably is, provided with free-swinging flap members 18 and 19 at front and rear of the crotch fly to which may be attached by safety-pins 20, or other appropriate fastening means, a protection cloth serving further to prevent exposure, or a catamenial bandage when necessary.

The fly crotch thus produced may be opened by unfastening the securing means 15-16 and folding the overlapping portions 6-7 outwardly along the wearer's legs, as shown in Fig. 3, or, after the parts 13 and 14 have been unfastened, they and portions of the parts 4 and 5 may be tucked inside the leg portions against the wearer's legs, as shown in Fig. 4. In either procedure, but particularly in the latter (Fig. 4), the wearer's hands are left free because the crotch fly will remain open and retracted from the zone of possible soiling without being held by the hands in such open condition.

Although the free tabs 13 and 14 are shown as fastened to the outside of the garment, which is preferred, it is practical to insert and fasten them inside the garment, that is to say, between the front panel of the garment and the wearer's body.

The protection cloth 21 may be used or not, as desired. If not used, soiling of the crotch of the garment, or its ultimate wearing out, does not necessitate the discarding of the whole garment, as the crotch construction is to be considered as a removable, replaceable unit, and it is apparent that instead of joining the crotch parts to the body by relatively permanent seams 2 and 3, they may be removably attached by suitable fastening means.

It will be understood, moreover, that the crotch construction of the invention, having reference particularly to Fig. 4, may be considered as a unitary assembly for application to garments not especially designed to receive it, as very little alteration of any of the known types of such garments, particularly panty-girdles, would be necessary to adapt them to its inclusion.

Obviously, also, the construction of the fly crotch is so simple and so practical in point of use that its purpose and mode of operation are immediately apparent. And, furthermore, this

simplicity makes unlikely errors in assembly and installation and faults in operation which would result in return of the garment to the merchant selling it.

6 While in normal condition of use this crotch construction will remain closed and will provide the desired uplift, due to its construction and mode of fastening, and will furnish full protection from exposure, it may be easily and quickly unfastened and opened, and held open by tucking its free tabs back along the wearer's legs.

Various changes and modifications are considered to be within the principle of the invention and the scope of the following claims.

What I claim is:

1. In a crotch construction for garments, particularly for women's undergarments of the panty-girdle type, two members for connection to the body of the garment at the front and rear and to adjacent leg portions thereof in the region of the crotch and having adjacent free edges arranged medially of the crotch and serving to form an openable fly extending through the crotch, and parts carried by said members and separable from said body for fastening said members in closed-fly condition with respect to said body and for exerting a reactive tension between the members and the body to provide an uplift at the crotch of the wearer.

20 2. In a crotch construction for garments, particularly for women's undergarments of the panty-girdle type, two members for connection to the body of the garment at the front and rear and to adjacent leg portions thereof in the region of the crotch said members having adjacent free edges arranged medially of the crotch and serving to form an openable fly extending through the crotch, the free edge of one of said members being designed to overlap the free edge of the other member, and means carried by said members and separable from said body for fastening said members in closed-fly condition with respect to said body and for exerting a reactive tension between the members and the body to provide an uplift at the crotch of the wearer.

35 3. In a crotch construction for garments, particularly for women's undergarments of the panty-girdle type, two members for connection to the body of the garment in the region of the crotch and having overlapping adjacent edges arranged to form an openable fly extending through the crotch, and means including extensions of said members substantially in alignment with the 50 overlapping edges attachable to and detachable from said body, said extensions when attached to said body serving to maintain said members in closed-fly condition and to exert a reactive tension between the members and the body to provide an uplift at the crotch of the wearer.

4. In a crotch construction for garments, particularly for women's garments of the panty-girdle type, two members for connection with the front and rear portions and leg portions of the 55 body of the garment in the region of the crotch and having normally overlapping free edge portions extending through the crotch and forming an openable fly therethrough, free extensions on said members in continuation of their overlapping 60 edge portions, fastening means on said extensions and complementary fastening means on adjacent parts of the garment body and offset laterally of the longitudinal center of said body, whereby the 65 free extension of the member on the right of the 70 crotch may be attached to the body at the left of

the longitudinal center thereof, and the free extension of the member on the left of the crotch may be attached to the body at the right of the longitudinal center thereof, for fastening said members in overlapping closed-fly condition and for exerting a reactive tension between them and the garment body to provide an uplift at the crotch of the wearer.

5. A crotch construction as claimed in claim

1, in which means are provided for the attachment of a protection cloth between the fly and the wearer's body.

6. A crotch construction as claimed in claim 5, in which means are provided upon the inner one of the overlapping edges for the attachment of a protection cloth between the fly and the wearer's body.

VICTOR A. FAEGRE.
